UNITED STATES PATENT OFFICE

2,188,729

RUNNING BOARD FOR RAILROAD CARS

George A. Steuber, Penfield, N. Y., assignor to
Despatch Shops, Inc., a corporation of New
York

Application February 13, 1939, Serial No. 256,138

3 Claims. (Cl. 105—457)

Running boards now commonly in use on railroad cars are of the same width from end to end, and normally the running board of one car is in alignment with the running board of an adjacent car, but in the weaving of a car and on curves and switches the ends of the running boards of adjacent cars become tangent with each other, leaving a void at one side, which voids are a menace to the safety of the trainmen 10 as in heavy rains, snows and the like, a trainman is apt to step into this void and fall from or between the cars.

The primary object of this invention is to provide a running board of sufficient length to project beyond the ends of a car, and provide these 15 projecting ends with materially wide lateral foot supporting wings, thus making such ends materially wider than the main body of the running board.

Another object of my invention is to provide a running board having ends materially wider than the main body of the board to provide a platform upon which a trainman may stand while operating ice hatch doors on refrigerator cars, thereby eliminating the building of the customary foot board framing around the ice hatch of such cars; and with these and other objects in view, my invention consists of the parts and combination of parts hereinafter described.

In the drawings:

Figure 1 is a detail perspective view of the top end portion of a refrigerator car embodying my invention.

Figure 2 is a top plan view of a car with my improved running board attached.

Figure 3 is a top plan view of another embodiment of my improved running board.

Figure 4 is a detail side elevation.

In one form of my improved running board for railroad cars it is made lattice or gridlike, and consists of the side pieces 1 extending the entire length of the board and lengthwise extending load supporting strips, or members, 2, said side pieces and strips 2 being interlocked with each other by means of the transverse bars. This interlocking may be accomplished by welding, or any other approved manner. This metal grid may be made, such, for example, from expanded metal, fine open mesh fabric, et cetera, according to the wish of the manufacturer and customer. These boards are of such length that the ends project a material distance beyond the ends of the car.

According to my invention these running boards are provided at their projecting ends with

side laterally extending wings 3, which are supported and secured to the ends of the wing boards by means of the supporting bars 4 and 5, which, in turn, are secured to the running board by rivets, or in any other approved way.

In another embodiment of my invention the running board is made up of wooden boards 6 suitably connected together, the ends of which board also project a material distance beyond the ends of the car, as described in connection 10 with the first named embodiment, and the board is provided with side laterally extending wings 7, thus making these projecting ends materially wider than the width of the main body of the running board.

These wings 7 are secured to the running board by means of supporting bars 8, and the entire projecting end structure of the running board is further supported by means of the brackets 9, one end of which is secured to the car while the 20 other end is secured to the projecting end structure of the running board.

The boards 6 are supported at intervals by the transverse bars 9.

The character of the material forming the running board is optional.

The materially widened projecting ends of the running board give a wider and safer footing between cars for the trainmen under a service condition, in addition to which these wider ends 30 provide a convenient and safe footing for trainmen in operating the ice hatches on refrigerator cars.

As will be seen from the drawings, the wings at the ends of the running boards extend rearwardly a considerable distance back over the roof of the car, and that in the case of refrigerator cars the rear ends of the wings are very close to the ice hatches.

What I claim is:

1. In a safety running board construction for railway cars, the combination with a car body and its roof, of a main runway platform extending centrally and longitudinally of the roof from end to end of the car, and laterally extending platform wings at opposite sides of each end of the main runway platform, the outer ends of the wings and end of the main platform at each end of the car extending outwardly to like degrees beyond the car end and the inner ends of the wings being of greater width than the said outer ends thereof and arranged to overlie the roof of the car.

2. In a safety running board construction for railway cars, the combination with a car body 55

and its roof, of a main runway platform extending centrally and longitudinally of the roof from end to end of the car, and laterally extending platform wings at opposite sides of each 5 end of the main runway platform, the outer ends of the wings and end of the main platform at each end of the car extending outwardly to like degrees beyond the car end and the inner ends of the wings extending inwardly over the 10 roof of the car, said wings being of minimum width at their outer ends and maximum width at their inner ends and gradually varying in width between said ends.

3. The combination with a car body and its 15 roof, said roof having hatch openings and doors therefor located adjacent each end of the car

on opposite sides of the longitudinal center of the roof, of a main runway platform extending longitudinally and centrally of the roof and between said hatch openings from end to end of the car, and laterally extending platform 5 wings at opposite sides of each end of the main platform, the outer ends of the wings and end of the main platform at each end of the car projecting outwardly beyond the car end and the inner ends of the wings extending inwardly be- 10 yond the car end over the roof toward the adjacent hatch openings and providing supports on which a trainman may stand to operate the hatch doors.

GEORGE A. STEUBER. 15
